DESIGN FOR A WHEEL

J Harold Hunt, Lansing, Mich., assignor to Motor
Wheel Corporation, Lansing, Mich., a corpora-
tion of Michigan

Application June 7, 1934, Serial No. 52,086

Term of patent 7 years

To all whom it may concern:

Be it known that I, J Harold Hunt, a citizen of the United States, residing at Lansing, in the county of Ingham and State of Michigan, have invented a new, original, and ornamental Design for a Wheel, of which the following is a specification, reference being had to the accompanying drawing, forming part thereof.

In the drawing:

Figure I is a side view of a wheel showing my new design;

Figure II is a perspective view of the wheel body shown in Figure I;

Figure III is an enlarged sectional view through a spoke taken on substantially the line III-III of Figure I; and

Figure IV is an enlarged profile view taken on substantially the line IV-IV of Figure I.

The distinctive features of the present design reside in the proportioning and contour of the outer face of the wheel and the web formations between the spokes. As clearly shown in Figure IV the spokes are more or less concave and merge at their roots into a substantially convex central dome. Substantially flat web portions are formed between the spokes beneath the generally elliptical openings.

I claim:

The ornamental design for a wheel as shown and described.

J HAROLD HUNT.
